WEATHER STRIP

George F. Wolff and Willard Congreve, Chicago,
Ill., assignors to Sager Metal Weatherstrip
Company, Chicago, Ill., a corporation of Illinois

Application January 21, 1939, Serial No. 252,084

2 Claims.

(Cl. 20—69)

This invention relates in general to weatherstripping, and more particularly to metal weatherstripping which is adapted to function as a parting bead or strip for window sash mounted in a window casing or frame.

A principal object of the invention is the provision of a combined metal parting bead and weatherstripping which is adapted for use either in a window frame having the usual parting bead recesses, or in a frame not provided with such recesses, whereby, in the latter case, the necessity of cutting the recesses is eliminated.

Another important object of the invention is the provision of a metal parting bead, so formed as to provide an interlocking slide and effective weather seal in cooperative relation with sliding members provided on wooden window sash, and having bearing portions for the end sliding surfaces of the window sash which make line contact therewith, rather than surface contact, for the purpose of reducing friction therebetween.

A further important object of the invention is the provision of such a combined metal parting bead and weatherstrip which is adapted to be so secured to the window frame that the parting bead portion thereof is resiliently displaceable to a certain extent relative to the window frame and sash.

Numerous other objects and advantages of the invention will be apparent as it is better understood from the following description, which, when taken in connection with the accompanying drawing, discloses a preferred embodiment thereof.

In the drawing,

Figure 1 is a partial perspective view showing the installation of a combined parting bead and weatherstrip embodying the features of the instant invention in connection with a window frame and the window sash associated therewith; and

Fig. 2 is a horizontal section of the same on an enlarged scale, with a slightly different type of window frame.

Referring more particularly to the drawing, reference numeral 11 indicates in general a portion of a window casing or frame of the box type which includes a side plank or wall member 12, having the usual parting bead receiving channel or recess 13, an outer rail or stop member 14 and an inner molding or stop member 15. The window illustrated also includes a pair of vertically slidable window sash 16. Since it is not intended that the instant invention be limited to application to the particular type of window

herein illustrated, further description thereof is thought to be unnecessary to an understanding of the invention.

Reference numeral 17 indicates in general a combined parting bead and weatherstrip embodying the features of the invention which comprises a central portion 18 and end portions 19 and 21. The member 17 is formed from a single strip of sheet metal, with the central portion 18 extending forwardly from the plane thereof to provide a substantially U-shaped, hollow strip or bead having side walls 22 and a front wall 23. From each side of the front wall 23, the metal of the strip is bent rearwardly in spaced relationship to the associated side wall 22, and is then folded inwardly back upon itself and forwardly into contact with the front wall 23, where it constitutes the forward end of the side wall 22. Two lateral walls 24 are thus formed which are disposed in parallel, spaced relationship to the side walls 22 and terminate at their inner ends in rounded edge portions 25 which are spaced well away from the plane of the end portions 19 and 21.

The member 17 is adapted to be positioned on the forward surface of the side plank or wall member 12, with the end portions 19 and 21 thereof directly adjacent the end sliding surfaces of the two window sash 16, and the central portion 18 opposite or over the channel or recess 13 and disposed between the sash to function as a parting bead therefor. The end portions 19 and 21 are each provided with a pair of parallel, longitudinal ribs or embossed portions 26 which constitute line contact bearing portions for the end sliding surfaces of the window sash 16. Directly adjacent its longitudinal edge, the end portion 19 is bent forwardly and then back upon itself to provide a flange 27 formed as an integral part of the member 17 and adapted to function as a stop for properly positioning the same on the side plank 12.

The member 17 is secured to the forward surface of the side plank 12 in the following manner. The outer rail 14 is kerfed or notched at 28 at its inner end adjacent the forward surface of the side plank 12 to provide a suitable space within which the outer edge of the end portion 19 of the member 17 may be disposed. The flange 27 will thus abut against the inner end surface of the outer rail 14 to properly align and position the member 17. Suitable longitudinally spaced apertures are provided in each of the end portions 19 and 21, adjacent their longitudinal edges, through which screws 29 may

be screwed into the side plank 12 to secure the member 17 thereto in the proper position, as determined by the flange 27. The inner molding 15 is then secured to the side plank 12 in the usual manner, with inner edge overlapping the longitudinal edge of the end portion 21 of the member 17.

Co-operating weatherstrips of angle form (Fig. 2), comprising metal sliding members or rails 31, are secured with one leg against the side 10 edge or sliding surface of each of the window sash 16 by suitable nails, or the like, 32. The other or free leg of each of these angle strips 31 extends forwardly in substantially parallel, spaced relationship to its associated sash 16, and is reinforced at its outer or forward edge by being folded back upon itself at 33. These folded edges 33 of the angle strips or rails 31 are disposed between the associated side walls 22 and folded flanges or lateral walls 24 of the central 20 or parting bead portion 18 of the member 17, and have a tight fit therewith to form an interlocking slide and effective weather seal. The folding of the several parts, as above described, provides rounded edges which avoid any scraping or undue friction between the relatively movable parts.

It will be noted also that the ribs 26 on the end portions 19 and 21 of the combined parting bead and weatherstrip 17 are extended forwardly a sufficient distance to provide clearance for the anchored legs of the angle strips 31. In this manner, there will be no contact between these anchored leg portions of the angle strips 31 and the member 17. The free legs of the angle strips 31 are so dimensioned as to terminate a substantial distance short of the junction of the walls 22 and 24 of the parting bead portion 18 of the member 17. In this manner, appreciable outward movement of the strips 31 and sash 16 relative to the member 17 is permitted, which may be caused by shrinkage of the window sash, for example. Further outward movement of the strips 31 and sash 16 will also be permitted without any danger of breaking the weather seal, because the particular construction of the member 17 and the manner of securing the same adjacent its ends to the side plank 12, as above described, allows limited outward flexing of the central portion 18 away from the side plank without impairing the weather-tight connection between the side plank and the end portions 19 and 21 of the member 17.

In Fig. 2, the side plank 12 has been illustrated as one not having the usual parting bead receiving channel or recess 13. This has been done for the purpose of showing that the instant invention is equally applicable for use either in the presence or absence of the usual parting bead

recess. In either case, or in any other installation, a substantially perfect weather seal is formed between the window frame and the member 17, while at the same time the parting bead portion 18 of the latter is resiliently displaceable to a certain extent relative to the window frame and/or sash. Also, with or without such displacement, a substantially perfect weather seal exists between the members 17 and 31.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. A weatherstripping, comprising an integral sheet metal member having end portions extending outwardly in substantially the same plane, and a central portion forming a hollow flange and extending forwardly from said plane to function as the usual parting bead for the window sash and having folded flanges extending substantially parallel to the sides of said central portion forwardly of said plane, said end portions being attached adjacent their outer edges to the side surface of a window frame to provide a tight weather seal therewith, and a metal strip attached to the window sash and having a flange projecting from said sash to beneath one of said flanges to be in interlocking engagement with said central parting bead portion to provide a tight weather seal therewith.

2. In a window, a strip for a window sash slidably disposed in a window frame, comprising two end portions lying in substantially the same plane with each other and extending the full inner vertical length of said frame and beyond and normal to said window sash, and attached adjacent their outer edges to the side surface of said frame, and a central portion forming a hollow flange integrally joined with said two end portions and extending from said plane to function as the usual parting bead for the window sash and provided with folded flanges extending substantially parallel to the sides of said central portion, and metal strips attached to the window sash and having flanges projecting from said sash beneath said folded flanges to be in interlocking engagement with said central parting bead portion in all positions of the sash to provide a tight weather seal therewith.

GEORGE F. WOLFF.
WILLARD CONGREVE.
